METHOD AND APPARATUS FOR
CONTROLLING BLAST FURNACES

Otto J. Leone, West Newton, Pa., assignor of one-half to David P. Leone, Donora, Pa.

Application May 20, 1947, Serial No. 749,238

14 Claims. (Cl. 263—29)

1

This invention relates generally to blast furnaces and specifically to a method and apparatus for controlling the drop in gas pressure through the charge of stock in the furnace. It is the general object of the invention to obtain a smoother and more regular descent of stock in the furnace shaft and to control the counterflow of the ascending gases so as to prevent or reduce to a minimum the "slips" which result from "hanging" stock and the building up of excessive pressure-drops through the stock.

The inadequacy of present methods of control to compensate for furnace irregularities often adversely affects the regularity of stock descent through the furnace shaft. For example, such factors as weight of the stock column, particle size and shape, gas density, gas composition (molecular weight), degree of packing, size of furnace (area and contours), moisture in the charge and blast, viscosity of gases, wall friction, blast pressure, blowing rate and blast temperature are all factors which vary the effective voids and pressure-drop through the furnace stock. I compensate for variations in these factors by means of a differential pressure controller.

In a stock charge of given effective voids condition, for example, increasing the blowing rate and hot blast temperature, or either of them will increase the pressure-drop through the stock. If this pressure-drop is too high, hanging and slipping of the furnace charge will result, with consequent loss in furnace efficiency, increased tendency toward channelling of gases, and high dust losses.

Under present-day conditions, the furnace operator may vary some of the above-mentioned factors, such as weight of stock (by stock-level control), particle size, gas density, blast temperatures, blowing rate, or size of furnace (by design). Other factors are present, however, over which the operator has little or no control, such as irregularities in gas distribution which result from differences in degree of packing or differences in effective voids distribution across the charge; changes in particle size due to crushing or abrasion, and differences in rate of stock descent at various distances radially from the center of the furnace, or because of changes in cross-sectional area of the furnace shaft. All these factors affect the pressure-drop through the furnace.

At the high blowing rates now usually maintained, producing excessive pressure-drop, there is a tendency for small particles to become suspended when a critical velocity is exceeded. This

2

change in "lifting velocity" causes the lifting of particles whose suspension decreases the pressure-drop through the charge. Because of the unequal velocity distribution across the area traverse of the stock, however, there is a tendency to channel where the lifting velocity is highest. The lower the gas velocity, the less the tendency to form channels of high gas velocity and high dust-carrying capacity. I employ a differential pressure controller to keep the gas velocities below the critical velocity.

In present-day furnace operation, the operator is not aware of a hanging condition until an excessive pressure-drop has built up or the furnace has slipped. Corrective action cannot, therefore, be applied in time. By my invention, using pressure-drop control, corrective action may be applied at the correct time to eliminate furnace hangings, slips and consequent delays. Usually, just before a hanging condition occurs in a blast furnace, the blower attempts to maintain a certain rate of blowing wind. This causes the blast-supply pressure to increase on account of the increased resistance to flow of gases through the voids in the stock column. In order to maintain the mass rate of flow of gases through the stock, the pressure-drop, and therefore, the gas velocity through the stock, increases and may reach the critical lifting velocity mentioned above if the conditions which will finally cause hanging persist. It is the main object of this invention to measure and to control the pressure-drop by one of several methods.

Under present methods of furnace operation, the measurement of such conditions as blast rate of flow and pressures below or above the stock are not sufficient indications of the action of gas-solid contact within the furnace. Even if these conditions were controlled, the occurrence of channelling with resultant change in pressure-drop through the column might not be detected and corrected. The measurement or control of pressure-drop across the stock, in addition to the measurement or control of such conditions as gas flows or pressures at any particular location, provides an additional tool for obtaining better furnace operation. To this end, I regard the voids in the bed of solids in terms of an "equivalent orifice." That is, the furnace restriction could be likened to an orifice plate placed in a pipe line. If the pressure above or below the orifice be controlled to a given value, the pressure-drop for a given orifice area and flow (blowing) rate would remain constant. Actually, however such ideal conditions do not exist in the blast furnace.

What has been termed the "equivalent orifice" is not actually a fixed orifice or resistance, but has variable values of effective area or restrictive resistance which depend upon variable factors previously mentioned as affecting the gas flow through the stock voids.

Therefore, even with pressure control applied to a furnace, slips and hangings can occur if the pressure-drop increases to a critical value. On the other hand, if channelling of gases occurs in a pressure-controlled furnace, a decrease in pressure-drop across the stock would occur at any given blowing rate. This decrease in pressure-drop would tend to raise the pressure at the top of the furnace, to counteract which the pressure-control valve would tend to move to a more open position so as to restore the pressure at the top of the furnace to the set control point. It is obvious then that, while the valve movement would be correct to maintain the set top pressure, it would not compensate for the change in pressure-drop and, therefore, would not counteract the increased dust-carrying capacity due to channelling of gases. It is a further object of this invention, therefore, to use a differential pressure controller in conjunction with straight pressure-control means as one method of operation.

A complete understanding of the invention may be obtained from the following detailed description which refers to the attached drawings showing various embodiments and practices contemplated by my invention. In the drawings,

Figure 1 is a schematic diagram showing a blast furnace and one form of control system therefor according to my invention embodying a differential pressure controller;

Figure 2 is a similar diagram showing a modified control system utilizing two separate pressure controllers to control the pressure-drop across the furnace; and

Figure 3 is a similar diagram showing a more complete system incorporating additional measurement and control elements so as to effect closer control.

Figure 1 illustrates one form of control system according to the invention applied to a blast furnace 5 so as to permit the measurement and control of the pressure drop through the furnace stock. A blower 6 forces air through hot-blast stoves 7 and into the blast furnace by means of tuyeres which lead from the hot blast line 8. After passing through the stock charge, the gases leave the furnace by means of downcomers 9 and pass to the dust-catcher equipment. For a given blast rate, and a given state of voids in the stock, there will exist a definite pressure drop through the stock. A change in any of the aforementioned factors which affect the pressure drop will cause it to change, with consequent change in the furnace operation which in some cases may cause derangement of stock and gas movements. Figure 1 shows a control system including a differential pressure controller 10 connected to measure a pressure drop that will be indicative of the stock-charge resistance and control correctively a restrictive valve or valves in the flue gas mains leaving the furnace.

The differential pressure controller 10 which may be of the proportional type, measures the difference between the static pressures at locations indicated by 11 and 12, connection between the points of static pressure measurement and the measuring device being made by pipe lines 13 and 14. Alternately, this measurement can be made by connecting valved branch lines 15

and 16 to locations closer to the stock, as for example, between any horizontal planes on the stack proper, as indicated by taps marked 17 and 18. These last connections may be single pressure taps or may use piezometer rings with multiple pressure connections between ring and furnace shaft so as to obtain average pressures.

The controller 10 includes automatic control means to regulate the pressure-drop between the locations indicated above to a predetermined fixed value as set on the controller; this controller of which various types are commercially available, may be non-indicating, indicating, recording or indicating-recording. When the pointer of the controller 10 deviates from the set control point or control limits, the control mechanism causes corrective adjustment of a restrictive valve 19 in the downcomer 9 by means of a power operator 20, this action being in such a direction as to restore the pressure-drop value to the set point or limits. Although I have shown the controller and operator as separate components they may be combined into one integrated, self-contained unit.

In order to preclude any possibility of upsetting the controller action by slight disturbances in pressure-drop caused by movement of the large bell 21 during filling operations, an interlocking device may be incorporated to operate in conjunction with the above controller, this interlocking device operating from the opening and closing of the bell, and so arranged to render the control valve inoperative by locking either the valve position or the differential impressed on the controller, or by locking both. This last action may be controlled by the use of an automatic pressure-locking valve on both the pressure lines. Referring to Figure 1, I show an interlocking switch 22 operated by a suitable mechanical connection to the bell rod 23, and electrically connected by a circuit 24 to electrical shut-off valves 25 on each of the pressure impulse lines. When the bell 21 is in the closed position, switch 22 maintains valves 25 in the pressure impulse lines open; when the bell rod 23 moves to open the bell, switch 22 causes valves 25 to close so as to lock the pressures into controller 10 and prevent movement of the controller pointer or power operator 20 that would otherwise result if the bell movement caused an appreciable change in the gas pressure at the top of the furnace. In Figure 1 I show in addition to the interlocking valve mechanism 21, an interlocking relay 26 connected in circuit 27 by which controlled power is delivered to the valve operator 20; relay 26 may also be connected to interlock 22 by circuit 24 so that the power circuit will be opened during opening of the bell 21 as during charging operations. A hot-blast controller 28, connected by two connecting leads 29 to a thermocouple element 30, and by means of a power circuit 31 to a cold-air mixer valve and power unit 32, provides a pyrometer system that will bypass the required amount of cold air around the heating stoves to the hot-blast side thereof, so as to maintain the temperature of element 30 substantially constant.

Although in Figure 1 I show the pressure-drop controller 10 operating a restrictive valve 19 in the downcomer leaving the furnace, the controller may just as well regulate a valve in the blast main 8 leading to the furnace or, a bleeder or snort valve 33 or, controller 10 may regulate other corrective devices as shown in Figure 3 and to be described later.

In Figure 1 a temperature element 34 is connected by leads 35 to a temperature compensator which is incorporated in the differential controller 10. Temperature compensation may thus be accomplished for both hot-blast and exit-gas densities by regulating the hot-blast temperature to a constant value and by automatically correcting the controller 10 by the variable exit-gas temperature. Elements 30 and 34 should be reasonably close to their respective pressure taps 11 and 12. As an alternate correction, element 30 could operate the compensator in controller 10 and the temperature at element 34 be maintained constant by using the top-gas constant-temperature controller 53 illustrated in Figure 3; or as also shown in Figure 3, both temperatures can be controlled to substantially constant values.

Figure 2 illustrates another alternate method of control utilizing individual pressure controllers 36 and 37 instead of the differential controller 10 shown in Figure 1, and by causing these pressure controllers to operate the power operators of valves 38 and 39 located below and above the furnace stock, to maintain the static pressures at points 11 and 12 at predetermined values as set on the controllers. In this manner the difference between the static pressures at these points will be maintained substantially constant at a value below the critical value. Although Figure 2 shows the controllers operating valves restricting the air-blast and exit-gas lines, respectively, the method of controlling individual pressures is not to be limited to the control of pressure valves only but may be combined with other control functions as mentioned, for example, where a direct measurement of differential pressure is made. For example, pressure controller 36 could maintain constant pressure at points 11 or 17 by operating snorter valve 33, or by regulating the blower output pressure. Likewise controller 37 could be made to operate an atmospheric relief valve. As in the case of the differential type controller, the individual controllers 36 and 37 could incorporate gas and air-temperature measuring and compensating mechanisms similar to those described for use with the differential pressure controller.

I may also include in the system of Figure 2 a differential-pressure indicator or recorder 40 in addition to the pressure controllers so as to afford a means of measuring directly the pressure drop across the pressure taps. In addition this instrument may incorporate a control mechanism to operate, for example, a third restrictive valve 41 located either ahead of valve 38 or after valve 39. This last arrangement is an improvement over the method using the two pressure controllers 36 and 37 only in that, by using a suitably designed differential-pressure manometer, it is possible to use a more open scale to cover a more narrow range of pressure-drop than would be possible otherwise. The reason is that there are inherent limitations in industrial types of pressure-measuring elements which limit the smallest increment of pressure change to a certain fraction of the total range. This method, then, offers the advantage of a vernier adjustment in addition to the closeness of control available by the method of Figure 2 using pressure controllers 36 and 37 only.

As compared to the method represented by Figure 1, this method offers an alternate method of compensating for density changes in the air

or gas. In addition to density compensation by the method just described, the auxiliary controller 40 may instead of controlling the power unit and valve 41 control the blower speed, or a valve in the hot-blast line, or snorter valve or, in addition to having controllers 36 and 37 operate their respective pressure-control valves, controller 40 could control the injection of cooling gases or vapors, or combustion-supporting gases such as oxygen into the blast furnace. Thus, although Figure 2 shows another system for the control of pressure drop, it is not limited to the use of the equipment shown in Figure 2. These controllers may operate with other equipment than valves, as illustrated in Figure 3.

With reference to the pressure compensation described in the last paragraph, a more simple, but slightly less accurate means of compensating the control system is obtained by using the pressure-drop controller 40 in Figure 2 and only one of the pressure controllers, preferably omitting the blast controller 36, since normal percentage changes of pressure and hence density, are much less at the bottom of the furnace than at the top of the furnace. Where further and closer density compensation is desired, the hot-blast temperature may be automatically controlled by means now commercially available, and the top temperature may be maintained constant by use of a temperature controller controlling a water-injection spray valve located in the furnace top as shown in Figure 3 and described in detail later. With this arrangement the control index of temperature controller 53 would be set at a point sufficiently below the normal top-gas temperatures so that the cooling spray will cool the top gas to a constant predetermined temperature. A principal advantage of this method is that it will give the effect of temperature compensation for gas density either in the case of the differential controller or where a gas-flow measurement is made in the gas line leaving the furnace for the purpose of metering the rate of flow of gas. Another advantage from an operating point of view is that it will eliminate one more variable in the furnace operation.

Instead of injecting spray water, in some cases where the top temperature is very low as occurs in some of the latest modern furnaces, I propose to inject a hot or cold gas instead of water. This gas may, for example, be clean blast-furnace gas. In modern furnaces operating under reduced gas velocity and longer gas retention time because of the excess height of the furnace stock, the gases are cooled to too low a temperature for best furnace operation. In this case I propose to inject a heated gas just below the stock line, and thus to raise the top gas temperature to a constant value.

Although I have described the use of a separate pressure controller and differential-pressure controller for density compensation of the pressure drop measurement, a pressure-compensated differential manometer may be used in which the pressure correction is automatically made inside the manometer in the same manner as is sometimes practiced in the art of orifice flow-metering of compressible fluids which have varying pressures. With this arrangement the pressure compensation may be applied to the blast air or top gas, or to some pressure tap between the tuyeres and top so as to give an average pressure correction or, again as in the case of flow-meter measurement just mentioned, an averaging type

pressure tube with end connections to the high- and low-pressure taps may be used.

Figure 3 shows an alternate means of furnace control by which other variables are measured and controlled. This system may be operated with all the elements as shown or some of the finer corrections may be eliminated, depending upon the degree of control desired.

With the arrangement shown in Figure 3, the differential-pressure controller 10 may be used to directly regulate or by interlocking with other controllers may regulate combinations of valves or other corrective devices shown as required to maintain the pressure drop across the furnace at desired values. For example, since the pressure drop is affected by humidity, density, blower speed or volume of air, and temperature of the blast, the controller may regulate these quantities directly or indirectly by interlocking or cascade operation.

To further describe one of these alternate methods, for example, the controller 10 in Figure 3, can regulate the flow of a cooling or heating fluid or gas in such manner as to cause the furnace to cool or get hotter, by (a) injecting moisture into or removing moisture from the blast by directly or indirectly regulating humidity-control equipment 42 or, (b) regulating the cold air mixing valve 32, so as to affect the hot-blast temperature or, (c) by combining the regulating actions of (a) and (b) into a more flexible control. Regulating any or all of these variables will affect the pressure drop.

Under the scheme just described, should the pressure drop increase because the furnace runs too hot, for example, controller 10 would move the cold-air mixing valve 32 to a more open position, or alternately, particularly if the cold-air mixing valve is too small, as is the case in many old furnaces, the controller 10 would, in addition, inject moisture in the form of steam or water spray by the humidity control equipment 42. This cooling of the blast and furnace stock will permit the passage of greater mass rate of air through the same voids in the stock. Alternatively, the steam valve in humidity controller 42 may be used in combination with the cold-air mixing valve 32 in such manner that moisture will be injected only when cooling is required. The cold-air valve 32 may be operated only to cut off cold air so as to raise the hot-blast temperature or it may be operated in conjunction with moisture injection for cooling and without moisture injection when hotter blast air is required. This means of operating two valves is well known in the art of automatic control and presents no difficulty from an operational standpoint. As an alternate to the method of moisture injection or humidity control, the controller 42 can be moved closer to the furnace stack and controller 10 can regulate the conditioning of the air by injecting relatively inert "quenching" gases to alter the chemical composition of the blast gases and cause the furnace to become more or less heated or cooled. Nitrogen or gases high in carbon monoxide, for example, would have a cooling effect at the bottom of the furnace, while a gas composition containing carbon dioxide would dissociate because of the high hearth temperatures, and would tend to cool the furnace by the endothermic reaction, and would affect the pressure drop.

In recent years there has been much discussion of using oxygen to enrich the air blast. The effect of injecting oxygen to enrich the blast, I

believe, would be to increase the hearth temperature but less blast would be required, if it were enriched with oxygen, to maintain a given reducing rate than if no enriching oxygen were used. The volume of reactant gases corresponding to the reducing rate would be less with enriched blast than with ordinary blast with normal oxygen, so that the pressure-drop through the furnace may be considerably decreased. The net effect on pressure-drop due to the hotter hearth and the smaller volume of reactant gases will depend upon the ratio of oxygen to blast air. It can be seen then, that the controller 10 can be used to regulate the flow of oxygen and other gases to maintain the pressure-drop below the critical value or at a constant value. While I have mentioned the quenching effect of other gases, they may serve other purposes such as to aid the reducing action in the furnace in the case of gases rich in carbon monoxide or hydrogen.

Should proportional type of control not be desired, this controller may be equipped for on-off type of control so as to give corrective action only when the pressure differential reaches predetermined limits above or below the predetermined point. It can be seen that this type of control would not necessarily be continuous and might be advantageous where a steam saving is desired at the sacrifice of some control accuracy.

In case temperature compensation for density changes is desired, as when it is desired to obtain more accurate blast-air or exit-gas flows, this may be accomplished by maintaining the temperature constant as by controlling the hot-blast temperature by use of the hot-blast controller and a cold-air mixing valve, or by cooling the top-gas temperature to a constant lower value than would otherwise normally exist. Alternatively, as in the case of pressure-compensation, a temperature-sensing device can transmit a loading force or impulse to a temperature-compensated differential-pressure manometer similar to that which was described for pressure compensation but having the compensation linkages inverted. Such measuring instruments are commercially available and are fairly standard.

In the same manner a sample of hot blast or discharge gases can be piped to a density or specific-gravity meter which in turn may apply a compensating loading force or pressure impulse to the compensated differential-pressure controller.

Referring to Figure 3, the pressure-differential controller 10 is connected by pipe lines 15 and 16 to measure the pressure-drop across the furnace, as between taps 17 and 18. This controller can operate valve power units 38 or 20 or 41, being interlocked by suitable transfer switches and interlocks 43 through 46, so that it may operate any of the valves. If it is desired, controller 10 may operate either the blast-air conditioning controller 42 or the blower-volume controller 47 by suitable setting of the transfer switch 43 and similar switches 48 and 49.

The electrical interlock switch 22 serves during opening of the bells to prevent the controller 10 from operating valves during this period. Circuit 24 connects switch 22 with power-operated valves 25 and interlocks 50, 51 and 52.

A top-gas temperature controller 53 is connected to a sensitive detector 34. Controller 53 is interlocked with controller 10 through interlock 43 so that it may operate valve 54 supplying

spray nozzles 55 or, if desired, correct the controller 10 for temperature variations.

An absolute humidity controller 56 operates from measuring mechanism 57 through two connections 58 and by means of connections 59 sends correcting impulses to humidity controller 42.

An air-blast flow-meter controller 60 shown also in Figure 1 measures air flow through a primary metering element by means of pipe lines 61 and operates the regulator 47 on the blowing engine by means of correcting impulse line 62. Controller 10 and controller 60 can be interlocked for cascade operation, as indicated by line 63.

A gas-volume controller 64 measures gas flow by means of a primary flow-metering element in 15 downcomer 9 and impulse lines 65. If desired, it can operate valve operator 41 by means of impulse-correcting line 66 or, alternately, by means of interlock connection 67, and setting transfer switches 43 and 46 as required, it can be operated in cascade with controller 10.

A top-pressure controller 68 is provided in case a non-compensated differential-pressure controller is used, to measure the gas pressure in downcomer 9 and operate valve 19 as required to keep the gas pressure constant at the top of the furnace.

A hot-blast temperature controller 69 operates from thermocouple 30 and circuit 29. Correcting impulses may be sent to either cold-air mixer valve 32 over circuit 31, or over a circuit 70 for cascade connection to controller 10 by proper setting of transfer switches 43 and 45. Temperature- and pressure-compensation mechanisms are usually incorporated in the differential-pressure controllers and controller 10 may be either an uncompensated or a pressure-compensated instrument. No extra outside pressure-impulse lines are needed since one or the other of the two pressure lines 15, 16 would also operate the pressure compensator.

As an alternate method of gas-density control a specific-gravity controller may be used to correct the differential controller for density change by applying a loading impulse, such as an air pressure to a compensating element in the differential controller 10. The specific-gravity controller would be used as an alternate to a pressure-compensated controller where finer corrections are desired than is possible with temperature or pressure correction only.

It will be appreciated that the various permutations and combinations described above affect the actual gaseous flow, without referral to standard conditions, in one or more parts of the new system by means of which the pressure-drop is controlled and maintained at a constant value or otherwise below the critical differential pressure value. Thus, a change in the gaseous flow at any particular part may impart a corrective change in the actual volume or in the rate of flow or in a combination of the two in such one or more parts of the new system.

Although I have confined my description to the iron blast furnace it is to be understood that pressure-drop control can be applied equally well to non-ferrous smelting furnaces which are similar to the iron blast furnace, and to certain types of gas generators which resemble blast furnaces in construction, using the same method of charging solid fuel and using counter-current flow of blast air, but which do not charge any flux or ore solids. The physical principles governing the orderly descent of the solid charge,

however, is the same as in the iron blast furnace.

Advantages of this controller may be summed up as follows:

1. Better furnace efficiency through more regular control of stock and gas flows, better working furnace, less hangings, slips, and channelling.

2. Decreased dust losses as result of less channelling and slips.

3. Improved fuel economy because of better gas distribution; permits use of highest possible blast temperatures and drier air on dry blast furnaces.

4. Less trouble due to poor coke and fine ores. Finer ores can be used than are now being used and with less attention to sizing.

5. Automatic control anticipates slips and applies corrective action in time, as contrasted to corrective measures being applied after slip occurs as under manual control methods.

6. Automatic pressure-drop control, by giving better and slower gas-velocity control through the center of the furnace, will put the operation of large-diameter furnaces on the same basis as small-diameter furnaces, particularly in regard to the relative output of iron per square foot of hearth area. Past experience indicates that most large-diameter furnaces will not take as much blast per square foot of hearth area as smaller furnaces, because of the poorer distribution of gas velocities. Pressure-drop control will reduce this difference.

7. Increased output will be more easily obtained with differential-pressure control.

Although I have illustrated and described but a preferred practice and various embodiments of the invention, it will be recognized that changes in the construction and procedure may be made without departing from the spirit of the invention or the scope of the appended claims.

I claim:

1. In a method of operating a blast furnace or the like having a shaft repeatedly charged with a heterogeneous stock of material, the steps comprising, blowing a heated atmosphere upward through said stock, removing reaction gases from the top of said furnace, measuring the static pressure of said heated atmosphere adjacent the bottom of said stock, measuring the static pressure of said reaction gases adjacent the top of said stock, controlling the difference between said static pressures to a value below that predetermined value at which said furnace has a tendency to generate slipping conditions therein, and effecting said controlling by selective variation of at least one of the temperature, pressure and rate of flow relationships of said heated atmosphere and said reaction gases.

2. In a method of operating a blast furnace system having a hearth, a bosh and a stack, means for supplying a heterogeneous charge of solid fuel, flux and ore adjacent the top of the stack, means for supplying blast air under pressure adjacent the hearth, and means for taking off gaseous products adjacent the top of the stack, the steps of feeding said charge to the furnace, maintaining it substantially filled, substantially continuously supplying blast air, and taking off gaseous products, the air and evolved gaseous products traveling upwardly through the interstices of the stock, periodically determining the pressure drop over at least the major portion of the stack, and regulating the gaseous flow in the system in accordance with such determination so as to maintain the pressure drop below a differential conducive to disorderly downward movement of the stock.

3. In a method of operating a blast furnace system having a hearth, a bosh and a stack, means for supplying a heterogeneous charge of stock adjacent the top of the stack, means for supplying blast air under pressure adjacent the hearth, and means for taking off gaseous products adjacent the top of the stack, the steps of feeding said charge to the furnace, maintaining it substantially filled, substantially continuously supplying blast air, and taking off gaseous products, the air and evolved gaseous products traveling upwardly through the voids of the stock, substantially continuously determining the pressure drop over at least the major portion of the stack, and substantially continuously regulating the gaseous flow in the system in accordance with such determination so as to maintain the pressure drop below a differential value conducive to disorderly downward movement of the stock.

4. In a method of operating a blast furnace system having a hearth, a bosh and a stack, means for supplying a heterogeneous charge of stock adjacent the top of the stack, means for supplying blast air under pressure adjacent the hearth, and means for taking off gaseous products adjacent the top of the stack, the steps of feeding said charge to the furnace, maintaining it substantially filled, substantially continuously supplying blast air, and taking off gaseous products, the air and evolved gaseous products traveling upwardly through the voids of the stock, substantially continuously determining the pressure drop over at least the major portion of the stack, and regulating the gaseous flow in the system in accordance with such determination so as to maintain the pressure drop substantially constant and at a value conducive to orderly downward movement of the stock in the furnace.

5. In a method of operating a system blast furnace or the like having a shaft repeatedly supplied with a heterogeneous charge of stock, means for supplying blast air under pressure adjacent the bottom of said blast furnace, and means for taking off gaseous products adjacent the top of said blast furnace, the steps comprising, feeding said charge to said blast furnace, maintaining it substantially filled, substantially continuously supplying blast air to said furnace and taking off gaseous products from said furnace, the air and evolved gaseous products traveling upwardly through the voids of the stock, substantially continuously determining the pressure drop over at least the major portion of the shaft, and substantially continuously regulating the blast air in accordance with such determination so as to maintain the pressure drop below a differential pressure conducive to disorderly downward movement of the stock.

6. In a method of operating a system blast furnace or the like having a shaft repeatedly supplied with a heterogeneous charge of stock, means for supplying blast air under pressure adjacent the bottom of said blast furnace, and means for taking off gaseous products adjacent the top of said blast furnace, the steps comprising, feeding said charge to said blast furnace, maintaining it substantially filled, substantially continuously supplying blast air to said furnace and taking off gaseous products from said furnace, the air and evolved gaseous products traveling upwardly through the voids of the stock, substantially continuously determining the pressure drop over at least the major portion of the shaft, and regulating the gaseous products flow in accordance with such determination so as to

maintain the pressure drop below a differential pressure conducive to disorderly downward movement of the stock.

7. In a method of operating a blast furnace system having a hearth, a bosh and a stack, means for supplying a heterogeneous charge of stock adjacent the top of the stack, means for supplying blast air under pressure adjacent the hearth, and means for taking off gaseous products adjacent the top of the stack, the steps of feeding said charge to the furnace, maintaining it substantially filled, substantially continuously supplying blast air, and taking off gaseous products, the air and evolved gaseous products traveling upwardly through the voids of the stock, substantially continuously determining the pressure drop over at least the major portion of the stack, substantially continuously regulating the gaseous flow in the system in accordance with such determination so as to maintain the pressure drop below a differential value conducive to disorderly downward movement of the stock, and preventing any change in said regulation of the gaseous flow during said feeding of said charge.

8. In a method of operating a blast furnace or the like having a shaft repeatedly supplied with a heterogeneous charge of stock, the steps comprising, feeding said charge to the furnace adjacent the top of said shaft, maintaining said furnace substantially filled, substantially continuously supplying blast air to the furnace adjacent the bottom of said shaft, substantially continuously taking off gaseous products from the furnace adjacent the top of said shaft, the air and evolved gaseous products traveling upwardly through the voids of the stock, periodically measuring the pressure drop generally across the height of the stock in the shaft, periodically measuring the pressure of said gaseous products, regulating the gaseous flow in the system in accordance with the determination of the pressure drop so as to maintain it below a differential value conducive to disorderly downward movement of the stock, said regulation being effected at least in part by varying the take-off of the gaseous products, and limiting said varying in accordance with said second-named measurement so as to maintain the pressure of said gaseous products so taken off below a value conducive to operating difficulties in said furnace.

9. In combination with a blast furnace system having a hearth, a bosh and a stack, means for supplying a heterogeneous charge of stock adjacent the top of the stack, means for supplying blast air under pressure adjacent the hearth, means for taking off gaseous products adjacent the top of the stack, the apparatus comprising, pressure responsive means connected axially across at least a substantial portion of the stack and adapted to determine the pressure drop generally across the stock, and means for regulating the gaseous flow in the system in accordance with said determination so as to maintain said pressure drop below a pressure differential conducive to the interruption of the orderly downward movement of the stock.

10. In combination with a blast furnace system having a hearth, a bosh and a stack, means for supplying a heterogeneous charge of stock adjacent the top of the stack, means for supplying blast air under pressure adjacent the hearth, means for taking off gaseous products adjacent the top of the stack, the apparatus comprising, pressure responsive means connected axially across at least a substantial portion of the stack

and adapted to determine the pressure drop generally across the stock, and means for varying the blast air to the furnace in accordance with said determination so as to maintain said pressure drop below a pressure differential conducive to the interruption of the orderly downward movement of the stock.

11. In combination with a blast furnace system having a hearth, a bosh and a stack, means for supplying a heterogeneous charge of stock adjacent the top of the stack, means for supplying blast air under pressure adjacent the hearth, means for taking off gaseous products adjacent the top of the stack, the apparatus comprising, pressure responsive means connected axially across at least a substantial portion of the stack and adapted to determine the pressure drop generally across the stock, and means for varying the gaseous products from the furnace in accordance with said determination so as to maintain said pressure drop below a pressure differential conducive to the interruption of the orderly downward movement of the stock.

12. In combination with a blast furnace system having a hearth, a bosh and a stack, means for supplying a heterogeneous charge of stock adjacent the top of the stack, means for supplying blast air under pressure adjacent the hearth, means for taking off gaseous products adjacent the top of the stack, the apparatus comprising, pressure responsive means connected axially across at least a substantial portion of the stack and adapted to determine the pressure drop generally across the stack, and means for varying the pressure of the blast air relative to the pressure of the gaseous products in accordance with said determination so as to maintain said pressure drop below a pressure differential conducive to the interruption of the orderly downward movement of the stock.

13. In a method of operating a blast furnace or the like having a shaft repeatedly charged with a heterogeneous stock of material, the steps comprising, blowing heated blast air upward through said stock in said furnace, removing reaction gases from the top of said furnace, measuring the static pressure of said blast air, measuring the static pressure of said reaction gases, controlling the difference between said

static pressures to a substantially constant value below that predetermined value at which said furnace has a tendency to generate hanging and slipping conditions therein, and effecting said controlling by selective variation of at least one of the furnace humidity, gas density, blast air volume and blast air temperature relationships.

14. In a method of operating a blast furnace system having a hearth, a bosh and a stack, means for supplying a heterogeneous charge of stock adjacent the top of the stack, means for supplying blast air under pressure adjacent the hearth, and means for taking off gaseous products adjacent the top of the stack, the steps of feeding said charge to the furnace, maintaining it substantially filled, substantially continuously supplying blast air, and taking off gaseous products, the air and evolved gaseous products traveling upwardly through the voids of the stock, substantially continuously determining the pressure drop over at least the major portion of the stack, substantially continuously regulating the gaseous flow in the system in accordance with such determination so as to maintain the pressure drop below a differential value conducive to disorderly downward movement of the stock, and locking the valve regulating the take-off of said evolved gaseous products during said feeding of said charge.
